UNITED STATES PATENT OFFICE.

JULIAN C. NYROP, OF HASTINGS, NEBRASKA.

POLE-ERECTOR.

1,317,816.

Specification of Letters Patent.

Patented Oct. 7, 1919.

Application filed April 9, 1919. Serial No. 288,807.

To all whom it may concern:

Be it known that I, JULIAN C. NYROP, a citizen of the United States, residing at Hastings, in the county of Hall and State 5 of Nebraska, have invented certain new and useful Improvements in Pole-Erectors, of which the following is a specification.

This invention relates to a device particularly designed for use in erecting telephone, 10 telegraph or analogous poles, and an object of the invention is to provide a device by means of which telephone, telegraph or analogous poles may be erected, by the utilization of a minimum number of men, and 15 also a minimum amount of manual labor, materially decreasing the cost of the erection of such poles as well as reducing the amount of time necessary for such work.

Another object of the invention is to provide a device for erecting telephone or telegraph poles, which is portable and comprises a bracing section which is lowered into the hole provided for receiving the butt of a pole, and rests against one side of the 25 said opening for securely bracing the erector structure during the erection of the pole.

A further object of the invention is to provide a pair of spaced angled bracing arms which have a saddle member attached thereto 30 against which the butt of a pole engages, during the initial stages of the erecting of the pole, the ends of which bracing members engage in the ground upon the opposite side of the hole to that which is engaged by 35 the portion of the erector which extends downwardly into the pole receiving hole.

A still further object of the invention is to provide a windlass construction for raising one end of a pole, to cause the butt end 40 of the latter to fall into the hole provided for receiving the same which windlass structure includes the longitudinally shiftable rotatable shaft which when shifted into one position will, upon rotation thereof rotate 45 a windlass drum for winding a pole raising cable thereon and when shifted into a different position will rotate a windlass drum for receiving the cable thereon to draw the depending portions of the pole erector from 50 the pole retaining hole in the ground.

Other objects of the invention will appear in the following detailed description taken in connection with the accompanying

drawings forming a part of this specification and in which drawings:

Fig. 1 is a side elevation of the improved pole erector, showing the same in position for erecting the pole.

Fig. 2 is a top plan of the erector.

Fig. 3 is an edge elevation of the pole 60 erector in position for erecting the pole.

Fig. 4 is a fragmentary section through the pole erector showing the depending portion thereof which is adapted to be positioned near the pole receiving hole in, the 65 ground, in a raised position.

Fig. 5 is a fragmentary plan of the windlass construction of the erector, showing the operating head therefor in position to raise the depending portion of the erector. 70

Fig. 6 is a fragmentary section on the line 6—6 of Fig. 5, illustrating a device to prevent accidental shifting of the operating shaft of the windlass.

Fig. 7 is a detail view of a saddle member 75 employed for connecting the raising cable to a pole.

Fig. 8 is a side elevation of the said saddle member.

Fig. 9 is a side elevation of a supporting 80 bearing formed upon the windlass structure, and

Fig. 10 is a cross section on the line 10—10 of Fig. 1.

Referring more particularly to the drawings, wherein like characters indicate like and corresponding parts throughout the several views, 1 indicates the main axle of the portable pole erector which has supporting wheels 2 rotatably mounted upon the spindle 90 ends thereof.

The supporting structure includes a pair of normally upright bars 3, and 4 attached to the axle 1 in any suitable manner such as by U-shaped bolts 5. The lower ends of 95 these supporting bars 3 and 4 have cross braces 5' connected thereto to which the inner or rear ends of horizontal braces 6 are connected. A super-structure 7 is carried by the upper end of the said upright braces 3 100 and 4 to which super-structure the ends of the horizontal portions 8 of the inclined braces 9 are attached. These braces 9 incline downwardly and forwardly from the superstructure 7 and they have their free 105 lower ends sharpened as shown at 10 for in-

sertion into the ground during the raising of the pole such as indicated at A to assist in preventing accidental movement of the erector structure at such times. The angled braces 9 are arcuate, near the rear ends of their angled portions, curving inwardly as clearly shown at 11 in Fig. 2 of the drawings, and the saddle 12 which may be constructed of sheet metal or any analogous material is attached to the inner surfaces of the curved portions 11.

A pair of spaced bearing members 13 are carried by the structure 7 and they rotatably support a shaft 14 which carries a cable receiving drum 15. The cables 16 and 17 are wound about the drum 15 at opposite ends thereof and they have their outer free ends hooked to a saddle structure 18 adapted to engage beneath the pole A at a point remote from the butt or end of the said pole. The saddle member 18 comprises a pair of bars 19 and 20 which are hingedly connected as shown at 21 to permit the spreading of the member for engagement with poles of different sizes. Each of the sections 19 and 20 has a plurality of spurs or spikes 22 attached thereto and inclining or curving inwardly as clearly shown in Figs. 7 and 8 of the drawings, the said spikes or spurs being adapted to bite into the wood of the pole A to securely connect the cables 16 and 17 to the pole.

The shaft 14 has a gear 23 mounted thereon which is adapted to mesh with a pinion 24 carried by the operating shaft 25 of the windlass structure of the erector, to rotate the shaft 14 and consequently the drum 15 by the rotation of the operating shaft 25. The operating shaft 25 has crank handles 26 attached to each end thereof and this shaft is slidably supported by the bearing structures 13 so that it may be shifted longitudinally to move the pinion 24 into or out of mesh with the gear 23 to control the rotation of the shaft 14 and consequently the drum 15 during the rotation of the operating shaft 24. A drum 27 is slidably supported, and is rotatably mounted upon the shaft 25, having the clutch section 28 upon one end thereof adapted to mesh with a clutch section 29 which is keyed to the operating shaft 24 to rotate the drum 27 by the rotation of the shaft 25 when the pinion 24 is out of mesh with the gear 23 as shown in Fig. 5 of the drawings. A latch or lock 30 is pivotally connected as shown at 31 to the structure 7 and it is provided with a recess 32 adapted to engage over the shaft 25, between the clutch sections 28 and 29 when the shaft 25 is shifted to move the pinion 24 in mesh with the gear 23 as shown in Fig. 2 of the drawings, to prevent accidental shifting of the shaft 25 during its rotation, sufficient to move the clutch sections into operative engagement. This latch member 30 is also

adapted to engage behind the clutch section 29 when the shaft 25 is shifted to move the clutch sections 28 and 29 into operative relation and prevent shifting longitudinally of the shaft 25 during the rotation thereof at 70 such times, and consequently prevent accidental disconnection between the shaft 25 and the drum 27.

A cable 33 is connected to the drum 27 and to the lower end of the longitudinally movable structure 34 which is adapted to extend into a hole as indicated at B which has been dug to receive the butt of the pole A. This structure 34 includes a pair of angled irons 35 and 36, which are connected at their upper 80 and lower ends by suitable angled irons 37 and are braced intermediate their ends by suitable bracing means 38. The cable 33 is connected to the angle iron 37 at the lower end of such structure, so that when the drum 27 is rotated for winding the said cable thereon, the structure 34 will be moved upwardly out of the hole or opening B.

In use, the erector structure is pushed to a position adjacent the hole B which has previously been dug at the desired place, and the drum 27 is rotated, through the medium of the shaft 25 for lowering the structure 24 into the hole B, in such a position that the said structure will engage against one side 95 of the hole. After this erector has been thus positioned, the cables 16 and 17 are connected to the pole A, the butt of which has previously been moved in close proximity to or over the hole B as shown in Fig. 1 100 of the drawings, in any suitable manner, preferably by means of the saddle structure 18. After the cables 16 and 17 have been connected to the pole A, the shaft 25 is shifted longitudinally for moving the pinion 105 24 into engagement with the gear 23, and consequently moving the clutch section 29 out of engagement with the clutch section 28, arresting rotation of the drum 27 by the rotation of the shaft 25. When the pinion 24 110 meshes with the gear 23, the rotation of the shaft 25 will be imparted to the drum 15, for winding the cables 16 and 17 thereon. During the winding of the cables 16 and 17 upon the drum 15, the engagement of the butt of 115 the pole A against the substantially semi-cylindrical saddle 12 will prevent the butt end of the pole from raising, and consequent action will be that the tip or outer end of the pole will be raised off the ground and 120 after this tip or outer end has been raised a sufficient distance, gravity action will cause the pole A to slide into the hole B, the said pole being guided, to a certain extent, by the saddle structure 12. During the operation 125 of raising the pole, any movement of the erector structure under action or pressure of the pole thereagainst will be prevented, through the medium of the structure 34 which has been lowered into the hole B and 130

the pointed end 10 of the angled bracing 9 will engage into the ground as clearly shown in Fig. 1 of the drawings.

After the butt of the pole A has been lowered into the opening B the shaft 25 is again shifted, or if it is desired, prior to the said shifting, the shaft may be rotated for unwinding the cables 16 and 17 from the drum 15. However, these cables may be manually 10 unwound if so desired, when the shaft 14 is disconnected from the shaft 25. Thus, after the cables 16 and 17 have been disconnected from the pole A and the shaft 25 has been shifted to move the clutch 29 into 15 engagement with the clutch section 28, further rotation of the shaft 25 will rotate the drum 27 raising the structure 24 out of the hole B. The erector may then be moved or backed away from the pole, and the entire 20 structure or erector may be tilted upon the axle 1 as a pivot through the medium of the structure 34 to permit the said structure to be moved into a substantially horizontal position, transferring the entire weight of the 25 erector structure from the braces 9 and structure 34 upon the axle 1 for facilitating the transportation of the erector from one place to another.

Changes in details may be made without 30 departing from the spirit of this invention, but;

I claim:

1. In a pole erector, the combination, of a supporting axle, a supporting frame carried by said axle, a longitudinally movable bracing structure carried by said frame and adapted to be extended into a pole butt receiving hole, and forwardly extending downwardly inclining braces carried by said 40 supporting frame.
2. In a pole erector, the combination, of a supporting axle, a supporting frame carried by said axle, a longitudinally movable bracing structure carried by said frame and adapted to be extended into a pole butt receiving hole, forwardly extending downwardly inclining braces carried by said supporting frame, and means carried by said frames for raising and lowering said bracing structure.
3. In a pole erector, the combination, of a supporting axle, a supporting frame carried by said axle, a longitudinally movable bracing structure carried by said frame and adapted to be extended into a pole butt receiving hole, means carried by said frame for raising and lowering said bracing structure, a windlass drum rotatably carried by said frame, cables connected to said drum for winding thereon, and means for connecting said cables to a telegraph pole for erecting the same upon the winding of the cables upon said drum.
4. In a pole erector, the combination, of a supporting axle, a supporting frame car-

ried by said axle; a longitudinally movable bracing structure carried by said frame and adapted to be extended into a pole butt receiving hole, means carried by said frame for raising and lowering said bracing structure, a windlass drum rotatably carried by said frame, cables connected to said drum for winding thereon, means for connecting said cables to a telegraph pole for erecting the same upon the winding of the cables 75 upon said drum, an operating shaft rotatably carried by said supporting structure and mounted for longitudinal movement, and means for connecting said operating shaft and said drum, said shaft being movable to disconnect it from said drum.

5. In a pole erector, the combination, of a supporting axle, a supporting frame carried by said axle, a longitudinally movable bracing structure carried by said frame and adapted to be extended into a pole butt receiving hole, a windlass drum rotatably carried by said frame, cables connected to said drum for winding thereon, means for connecting said cables to a telegraph pole 90 for erecting the same upon the winding of the cables upon said drum, an operating shaft rotatably carried by said supporting structure and mounted for longitudinal movement, means for connecting said operating shaft and said drum, said shaft being movable to disconnect it from said drum, means adapted to be operated by said drum, means adapted to be operated by said operating shaft for raising said bracing structure, and means for preventing 95 operation of said bracing structure raising means during rotation of said windlass drum.

6. In a pole erector, the combination, of a supporting axle, a supporting frame carried by said axle, a longitudinally movable bracing structure carried by said frame, and adapted to be extended into a pole butt receiving hole, a windlass drum rotatably carried by said frame, cables connected to said drum for winding thereon, means for connecting said cables to a telegraph pole for erecting the same upon the winding of the cables upon said drum, an operating shaft 100 rotatably carried by said supporting structure and mounted for longitudinal movement, means for connecting said operating shaft and said drum, said shaft being movable to disconnect it from said drum, means adapted to be operated by said operating shaft for raising said bracing structure, and means for preventing 105 operation of said bracing structure raising means during rotation of said windlass drum.

7. In a pole erector, the combination, of a supporting axle, a supporting frame carried by said axle, a longitudinally movable bracing structure carried by said frame and adapted to be extended into a pole butt receiving hole, means carried by said frame for raising and lowering said bracing structure, a windlass drum rotatably carried by said frame, cables connected to said drum for winding thereon, and means for connecting said cables to a telegraph pole for erecting the same upon the winding of the cables upon said drum, and forwardly extending downwardly inclining braces carried by said frame, said braces having their forward ends sharpened for insertion into the ground.

7. In a pole erector, the combination 130

of a supporting axle, a supporting frame carried by said axle, a longitudinally movable bracing structure carried by said frame and adapted to be extended into a pole butt receiving hole, a windlass drum rotatably carried by said frame, cables connected to said drum for winding thereon, means for connecting said cables to a telegraph pole for erecting the same upon the winding of the cables upon said drum, an operating shaft rotatably carried by said supporting structure and mounted for longitudinal movement, means for connecting said operating shaft and said drum, said shaft being movable to disconnect it from said drum, means adapted to be operated by said operating shaft for raising said bracing structure, means for preventing operation of said bracing structure raising means during rotation of said windlass drum, forwardly extending downwardly inclining braces carried by said frame, said braces having their forward ends sharpened for insertion into the ground, a substantially semi-cylindrical saddle carried by said braces and adapted to be engaged by the butt of a pole during the erecting thereof.

8. In a pole erector, the combination, of a supporting axle, a supporting frame carried by said axle, a longitudinally movable bracing structure carried by said frame and adapted to be extended into a pole butt receiving hole, an operating shaft rotatably carried by said frame for longitudinal movement with respect to the frame, a drum loosely mounted upon said shaft, means carried by said shaft for operatively connecting the shaft to said drum, for rotating the drum by rotation of the shaft, a cable connected to said drum, and to the lower end of said bracing structure whereby the bracing structure will be elevated upon the winding of the cable upon said drum.

9. In a pole erector, the combination, of a supporting axle, a supporting frame carried by said axle, a longitudinally movable bracing structure carried by said frame and adapted to be extended into a pole butt receiving hole, an operating shaft rotatably carried by said frame for longitudinal movement with respect to the frame, a drum loosely mounted upon said shaft, means carried by said shaft for operatively connecting the shaft to said drum for rotating the drum by rotation of the shaft, a cable connected to said drum, and to the lower end of said bracing structure whereby the bracing structure will be elevated upon the winding of the cable upon the drum, and means carried by said supporting frame for engagement with said shaft to prevent accidental rotation of said drum by said shaft.

10. In a pole erector, the combination, of a supporting axle, a supporting frame car-

ried by said axle, a longitudinally movable bracing structure carried by said frame and adapted to be extended into a pole butt receiving hole, an operating shaft rotatably carried by said frame for longitudinal movement with respect to the frame, a drum loosely mounted upon said shaft, means carried by said shaft for operatively connecting the shaft to said drum for rotating the drum by rotation of the shaft, a cable connected to said drum, and to the lower end of said bracing structure whereby the bracing structure will be elevated upon the winding of the cable upon the drum, means carried by said supporting frame for engagement with said shaft to prevent accidental rotation of said drum by said shaft, a second drum rotatably supported by said frame, a gear connected to said second drum, a pinion upon said operating shaft, and cables connected to said second drum and adapted for engagement with a pawl to raise the latter upon winding of the cables upon the second drum, said pinions being shifted out of meshing engagement with said gears when said operating shaft is operatively connected to said first named drum.

11. In a pole erector, the combination, of a supporting frame, a longitudinally movable bracing structure carried by said frame and adapted to be extended into a pole butt receiving hole, braces carried by said supporting frame, and means carried by said frames for lowering and raising said movable structure.

12. In a pole erector, the combination, of a supporting axle, a supporting frame carried by said axle, a longitudinally movable bracing structure carried by said frame and adapted to be extended into a pole butt receiving hole, and braces carried by said frame.

13. In a pole erector, the combination of a supporting frame, a longitudinally movable bracing structure carried by said frame and adapted to be extended into a pole butt receiving hole, braces carried by said frame, means carried by said frame for raising and lowering said movable structure, and a substantially semi-cylindrical saddle carried by said braces and adapted to be engaged by the butt of a pole during the erecting thereof.

14. In a pole erector, the combination, of a supporting frame, a longitudinally movable bracing structure carried by said frame, operating means for said bracing structure, pole raising means, means for operating said pole raising means and said bracing structure operating means, and means to prevent synchronous operation of said pole raising means and said bracing structure operating means.

15. In a pole erector, the combination, of

a supporting axle, a supporting frame carried by said axle, a longitudinally movable bracing structure carried by said frame and adapted to be extended into a pole butt receiving hole, means carried by said frame for raising and lowering said bracing structure, a windlass drum rotatably carried by said frame, cables connected to said drum for winding thereon, means for connecting said cables to a telegraph pole for erecting 10 the same upon winding of the cables upon said drum, and means to prevent synchronous operation of said windlass and said bracing structure raising and lowering means.

JULIAN C. NYROP.
